[57] CLAIM

[21] Appl. No.: **88,177**

The ornamental design for an electrosurgical generator,
 substantially as shown.

[22] Filed: **Oct. 25, 1979**

DESCRIPTION

[51] Int. Cl. .... **D24—01**
 [52] U.S. Cl. **D24/8; D24/17**
 [58] Field of Search 128/303.14, 400, 401,
 128/402; D24/8, 17, 21

FIG. 1 is a perspective view of the electrosurgical generator; showing our new design;

FIG. 2 is a rear view of the electrosurgical generator;
 FIG. 3 is a top plan view of the electrosurgical generator; and

FIG. 4 is a side elevational view of the electrosurgical generator, the other side view being identical thereto;
 FIG. 5 is an enlarged front elevational view of the electrosurgical generator.
